UNITED STATES PATENT OFFICE

2,495,479

BRA

Lee Naeger Reger, Burbank, Calif.

Application December 1, 1945, Serial No. 632,178

4 Claims. (Cl. 2-42)

1

This invention relates to garments and more particularly to a brassière, known in the trade as a bra.

The primary object of this invention is to provide a bra of simple, inexpensive construction and of such flexibility of design that it may be worn in various ways to obtain a variety of effects.

Another object of the invention is to provide a bra which can be constructed as a generally flat unfitted article of apparel and which may be donned and draped on the person of a wearer in various ways.

A corollary object of the invention, therefore, is to provide a bra which can be made in two or three key sizes and yet is adapted to be comfortably and suitably worn by persons varying in size over a wide range.

This invention possesses many other advantages, and has other objects which may be made more easily apparent from a consideration of one embodiment of the invention. For this purpose there is shown a form in the drawings accompanying and forming part of the present specification. This form will now be described in detail, illustrating the general principles of the invention; but it is to be understood that this detailed description is not to be taken in a limiting sense, since the scope of the invention is best defined by the appended claims.

In the drawing:

Figure 1 is a perspective view of a bra constructed in accordance with this invention and shown in position on the body of a wearer;

Figure 2 is a similar view showing the bra partly donned;

Figure 3 is a back view showing the bra in the process of being donned;

Figure 4 is a broken view of the bra in flat condition to emphasize its structural features; and,

Figure 5 is a fragmentary view similar to Figure 4, showing a modification of the invention.

Referring first to figures 4 and 5, the bra which is illustrated comprises, generally, a pair of wings 5 extending oppositely from each other and connected by a halter 6.

The wings 5 as shown in Figure 4, each comprise an elongated rectangular panel having longitudinal edges 7, an end edge 8, and a preferably puckered or pleated end 9. The wing 5 which is shown in Figure 5, is somewhat modified in that its longitudinal edges 7a are curved toward each other at an intermediate portion of

2

the wing to provide a neck 10 which is narrower in width than the general width of the wing.

The halter 6, in both forms of the bra which is shown, comprises a strap 11 which has portions 12 connected to and coextensive with the pleated ends 9 of the wings, and which has a loop portion 13 connecting the upper ends of the portions 12. A back strap 14 connects the lower ends of the strap portions 12 and extends between the wings 5 of the bra.

The portion 15 of each wing 5 comprises a breast covering portion, the portion 16 of Figure 4, and the neck 10 of Figure 5 comprise a knotting portion of each wing, and the remaining end portion of each wing comprises a bow forming portion. The strap portions 12 are designed to extend vertically along opposite sides of the body of the wearer, the loop 13 to engage around the back of the neck of the wearer, and the back strap 14, to encircle the back of the wearer.

As seen in Figure 3, the bra is easily applied or donned by extending first one arm and then the other through the space 17 of the bra with the loop 13 and the back strap 14 across the back of the wearer. The garment is then adjusted to bring the loop 13 around the neck and the back strap 14 across the middle of the back of the wearer. In this condition, the wings 5 will hang pendant on either front side of the body.

By bringing the wing portions 15 across to cover the breast and forming a knot 18 by inter-looping the panels, as shown in Figure 2, the bra can be comfortably fitted to the body and thereby adjusted in accordance with body dimensions. Only a minor part of each wing is used for covering the breasts, leaving the major portions of said wings extending from the knot 18, as shown. Now, by inter-connecting these extending portions of the wings to form a bow 19 superposed over the breast covering portions 15, as shown in Figure 1, the draping of the bra on the figure is completed.

Normally, the looped portions 20 of the bow 19 are generally of sufficient stiffness to maintain their position across the body and will not fall. However, the ends 21 of the bow which comprise the ends of the wings, may require additional support to prevent their dropping. Accordingly, the upper corners of said ends 21 may be tucked in under the respective breast covering portions, as shown at 22, so that the garment is neatly fitted and arranged.

From the foregoing it will be evident that a

simple bra structure has been provided; that the bra is easily, simply and quickly donned or removed; that a pleasing effect is obtained by draping the bra on the figure as described; and that the objects of the invention are realized by the structure described.

I claim:

1. A bra comprising a pair of elongated, substantially rectangular wings having juxtaposed ends, said wings extending oppositely from each other, a first strap having one end secured transversely of said wings to one end of one of said wings, extending in a generally U-shaped loop to the juxtaposed end of the other wing, the other end of said strap being secured transversely of said wings to said juxtaposed end of said other wing, and a second strap extending between said wings, and secured to the juxtaposed ends of said wings substantially at right angles to said first strap.

2. A bra comprising a pair of elongated oppositely extending fabric panels, a neck engaging halter having side portions connected by a loop, each of said panels having a corresponding end secured to one of said portions, and a back engaging strap joining the lower parts of said panel ends and normally extending therebetween in a direction longitudinally of the panels, said strap being adapted to extend across the wearer's back and beneath the arm pits for positioning the said panel ends adjacent the opposite sides of the chest, said panels being adapted to extend toward each other so that the inner end portions of said panels respectively cover the wearer's breasts, the outer end portions of said panels being of such length as to be adapted to be joined to form a bow overlying and substantially covering said breast covering portions, said panels, when joined, forming the sole connection between said halter side portions across the front of the wearer's body.

3. A bra comprising a pair of elongated oppositely extending fabric panels, the outer end portions of said panels being at least as wide as

the inner end portions, a neck engaging halter having side portions connected by a loop, each of said panels having a corresponding end secured to one of said portions, and a back engaging strap joining the lower parts of said panel ends and normally extending therebetween in a direction longitudinally of the panels, said strap being adapted to extend across the wearer's back and beneath the arm pits for positioning the said panel ends adjacent the opposite sides of the chest, said panels being adapted to extend toward each other so that the inner end portions of said panels respectively cover the wearer's breasts, the outer end portions of said panels being adapted to extend across the wearer's chest and to be joined intermediate their ends in a bow comprising the full width of the panels.

4. A bra comprising a pair of elongated fabric panels extending oppositely from each other, the inner end portions of said panels respectively constituting breast covering portions, and a halter connecting the inner ends of said panels, comprising a back engaging strap extending between the panels and a neck engaging loop extending upwardly from the upper edges of the panels, said inner end portions and the outer end portions of said panels being of substantial width and at least as wide as the intermediate portions, whereby said outer end portions may be formed into a bow of such size as to substantially cover said breast covering portions when the bra is worn.
